UNITED STATES PATENT OFFICE

2,153,367

ELECTRIC SWITCH

Frank C. De Reamer, Bridgeport, Conn., assignor
to General Electric Company, a corporation of
New York

Application August 14, 1936, Serial No. 96,058

4 Claims. (Cl. 200—67)

My invention relates to an electric switch and more particularly to an electric switch of the toggle operated type.

An object of my invention is to provide an improved switch having a longer life which may be manufactured economically.

What I consider to be novel and my invention will be better understood by reference to the following specification and appended claims when considered in connection with the accompanying drawing in which Fig. 1 is a plan view of the switch; Fig. 2 is a side sectional view along the line 2—2 of Fig. 1; Fig. 3 is a side sectional view along the line 3—3 of Fig. 1; Fig. 4 is an exploded view in perspective; Fig. 5 is a detail view of the rotary contact; and Fig. 6 is an end view.

Referring to the drawing, 10 indicates a base of insulating material having a central chamber 11 and side recesses 12 terminating in V-shaped slots 13 at the bottom. Stationary contacts 14 and 15 are mounted in one end of the base 10 extending into chamber 11 and stationary contacts 16 and 17 at the other end. Contacts 14 and 15 are secured in position in base 10 by means of two terminal plates 18 and 19. Terminal plates 18 and 19 rest against shoulders 20 and 21 respectively around side openings of chamber 11 and extend into slots 22 and 23 in the bottom of base 10. Contact 15 is secured to terminal plate 19 by integral projections 24 and 25 which are bent over into engagement with terminal 19. Contact 14 is similarly secured to terminal plate 18. Contacts 14 and 15 are connected together by a connector 26 which is secured to terminal plate 18 by a screw 27 and secured to plate 19 by screw 28. Screw 28 also serves as a binding screw to connect a conductor to contacts 14 and 15. With the two contacts 14 and 15 connected together the switch is adapted for use as a single pole switch. When it is desired to use the switch as a double pole switch the connector 26 is omitted. When a switch is used as a double pole switch it is highly desirable to insure the simultaneous connection of the circuit through the two contacts. For example, if one side of the circuit was completed through contact 14 before contact 15 was engaged then the whole of the arc produced on the making of the contact would be carried by contact 15 which in the case of use with gas filled lamps would be considerable and would result in the destruction of the contact. To insure the proper positioning of the two contacts 14 and 15 with respect to each other and thus insure a simultaneous connection through these contacts a plate 29 of insulating material is provided with

slots 30 and 31 which cooperate with the plates 18 and 19 respectively to hold the contacts 14 and 15 in exact alignment. Stationary contacts 16 and 17 are similarly secured in position by means of terminal plates 32 and 33 which engage in slots 34 and 35 respectively of plate 29. The operating mechanism consists of a U-shaped operating lever 36 with integral trunnions 37 and 38 which pivot in the V-shaped slots 13 of base 10. Two insulating discs 39 and 40 are carried by lever 36 by means of projections 41 and 42 which extend into corresponding slots 43 and 44 of discs 39 and 40. Disc 40 carries a contact 45 in a recess 46 by means of tangs 47 and 48 which extend into slots 49 and 50. The recess 46 is sufficiently deep so that the surface of contact 45 is flush with the surface of the disc 40. By this arrangement, it has been found that the life of the switch can be greatly extended due to the fact that when the bridging contact 45 moves into engagement with the stationary contacts it does not move the stationary contacts transversely and so does not tend to produce any arcs upon the momentary making and breaking of the circuit as the contact is made. By test, it has been found that the life of the switch is greatly increased by eliminating the possibility of such momentary arcs. The movement of lever 36 is accomplished by means of a spring 51 and an operating handle 52 pivoted in a threaded nozzle 53. Nozzle 53 is secured to a metal plate 54. Metal plate 54 is secured to base 10 together with a plate 55 of insulating material by means of screws 56 and 57.

From the foregoing it may be seen that a switch of simple construction which is economical to manufacture has been produced and has been provided with an improved arrangement of securing the contacts in position to reduce the arc on the making and breaking of the circuit and thus prolong the life of the switch.

What I claim as new and desire to secure by Letters Patents of the United States, is:

1. An electric switch comprising a base of insulating material having a central chamber and a side opening communicating therewith, stationary contacts extending into said central chamber, a terminal plate for securing each of said contacts in position by engagement with shoulders around the side opening of said chamber and seated in a slot in said base, and a plate of insulating material secured to said base and having slots to engage each of the terminal plates for properly positioning the stationary contacts with respect to each other.

2. An electric switch comprising a base of insu-

- lating material having a central chamber and a side opening communicating therewith, stationary contacts extending into said chamber, terminal plates for mounting said contacts resting 5 against a shoulder around the side opening of said chamber and seated in slots in said base, a plate of insulating material having slots for engaging the opposite ends of each of the terminal plates for properly positioning the stationary contacts, an operating lever pivoted in slots in the sides of said base, discs of insulating material secured to opposite sides of said lever, rotary contacts secured in recesses in said discs with the outer surfaces flush with the surfaces of the discs, 10 a spring connected to said lever, a plate secured to said base, and an operating handle pivoted in said plate engaging said spring for moving the operating lever from one position to another.
3. An electric switch comprising a base of insulating material having a central chamber and a side opening communicating therewith, stationary contacts extending into said central chamber, a terminal plate secured at right angles to each of said contacts and mounted in a slot in said base 15
- 20

and resting against shoulders around the side opening of said chamber, and a plate of insulating material secured to said base and having slots to engage each of the terminal plates for properly positioning the stationary contacts with respect 5 to each other.

4. In an electric switch, a base having a central chamber and a side opening communicating therewith, stationary contacts extending into said chamber, terminal plates for mounting said contacts, said plates being positioned in said side opening, a plate having slots for engaging the ends of said terminal plates for properly positioning the stationary contacts, an operating lever pivoted in said base, members of insulating material 10 secured to opposite sides of said lever, said members having recesses formed therein, contacts secured in said recesses with their outer surfaces flush with the surfaces of the members, and means for moving the operating lever to engage 15 and disengage the pivoted contacts with said stationary contacts.

FRANK C. DE REAMER.
